UNITED STATES PATENT OFFICE

FERDINAND H. BORM, OF CHICAGO, ILLINOIS

REGISTERING-DEVICE ACTUATING MEANS

Application filed March 26, 1927. Serial No. 178,524.

My invention relates to a registering device and the object of my invention is to provide a registering mechanism which is small and compact and arranged to be worn on the wrist in the manner of wearing a wrist watch and having a push button thereon for the purpose of registering the number of strokes made in playing golf.

Another object of my invention is to provide a device of the above indicated character having a plurality of discs with numbers thereon for indicating the number of times which the push button has been depressed and said registering discs are adapted to be operated by means other than the aforesaid push button for returning said discs back to their zero position for the purpose that will be hereinafter explained.

My invention will be best understood by reference to the accompanying drawings forming a part of this specification and in which,

Figure 1 is a top plan view of a register or counter incorporating my invention.

Figure 2 is an end view of that disclosed in Figure 1.

Figure 3 is a sectional view of that disclosed in Figure 1 and is taken on approximately the line 3—3 of Figure 4.

Figure 4 is a sectional view taken on approximately the line 4—4 of Figure 3.

Figure 5 is a sectional view taken on approximately the line 5—5 of Figure 4.

Figure 6 is a view similar to Figure 5 but showing the device with the push button in the depressed position.

Figure 7 is a rear view of that disclosed in Figure 1 having a cut-away portion and showing a modification of the push button arrangement for operating the same.

Figure 8 is a view similar to Figure 1 but showing a modified form of the main spring and a special attaching means thereon for a modified form of the push button.

Figure 9 is an enlarged view of a portion of that disclosed in Figure 8 and is taken on the line 9—9 in Figure 8.

In the drawings and for the purpose of illustration I have shown the preferred embodiment of my invention in which 10 rep-

resents a counting or registering device especially adapted for being worn on the wrist in the place of wrist watch and has counting discs 11 and 12 for the purpose of registering the number of strokes made in playing golf. A push button 13 is provided having a pin 16 secured thereto and passing through an opening 14 in the side of the casing 15 and having an engagement with an operating spring 17. When the push button 13 is depressed as shown in Figure 6 one end of the spring 17 engages with a tooth 18 on the wheel 12 and causes it to rotate on its axis 31.

In the front side of the casing 15 are provided openings 20 and 21 through which may be seen numbers which are on the face of the numbered discs 22 and 23 respectively. Between the wheel 12 and the disc 23 is interposed a spacer 24 and a disc 25. Said disc 25 is provided with one tooth 26 which is adapted to engage a tooth 27 on the toothed wheel 11 as shown in Figures 5 and 6. Since the disc 25 is provided with only one tooth, it is obvious that said tooth engages the wheel 11 only once during a revolution and as the wheel 11 has ten teeth the disc 25 must rotate ten times in order to cause wheel 11 to make one complete revolution on its axis 19.

The toothed wheel 11 and the numbered disc 22 are mounted on an irregular shaped member 28 and rotated therewith. Said member 28 is integral with the spacing member 29 and the pin or axis 19. In like manner the toothed wheel 12, the spacer 24, and the disc 23 are mounted on the irregular shaped member 30 which is integral with the pin or axis 31 and the spacer 32.

The casing member 33 is provided with bosses 34 and 35 provided with openings 36 and 37 respectively into which the pins 31 and 19 are positioned for rotary motion therein. In a similar manner the casing 15 is provided with openings 38 and 39 through which the pins 31 and 19 project as shown in Figure 4. Said pins 19 and 31 are provided on the outward ends with knurled knobs 40 and 41 respectively by which said members may be rotated independent of the operation of the push button 13.

The spring member 17 engages one end of the casing 15 and is bent into the form of a hair pin having a curved portion on one side thereof for frictionally engaging the wheel 12, as shown in Figure 5 and when the push button 13 is depressed the spring 17 is released from frictional engagement and allows the wheel to be rotated on its axis as hereinbefore explained. Another spring 42 is positioned along one side of the casing 15 and is provided with end members 43 and 44 for engagement with the teeth 18 and 27 respectively for preventing rotation of said toothed wheels in one direction. Said spring is of such strength that the frictional contact with the teeth 18 and 27 prevents the wheels from being easily displaced and they are accordingly held in position unless positive rotary force is given to them by means of the push button or the knurled knobs 40 and 41.

20 The casing portion 33 is provided with openings 45 through which a strap or bracelet may be passed for securing the counting device to the operator's wrist. As shown in Figure 4 the casing 15 is provided with lugs 46 which pass through the openings 45 into member 33 and said members 46 are bent down upon the member 33 for securing both portions 33 and 15 of the casing together.

30 In Figure 7 is shown a slight modification of my invention in which the spring member 17 is provided with an opening 47 therein. A push button 48 is secured to a pin 49 which is in turn secured into opening 47. The casing 15 is provided with a slot 50 through which the pin 49 is adapted to slide when the push button 47 is operated for operating the spring 17 in the same manner as hereinbefore explained.

40 In Figures 8 and 9 is shown one modification in which the spring member 17 is provided with a flange 51 having an opening 52 therein. A push button 53 is secured to a pin 54 which is in turn secured into opening 52 so that when the push button 53 is moved longitudinally of the casing, the spring 17 is operated as hereinbefore explained. The casing 15 is provided with the slot 55 through which the pin 54 may oscillate in its operation of the spring 17.

50 The operation of my invention is believed to be obvious from the foregoing description in that the push rod 16 or one of the push buttons 48 or 53, as the case may be, are adapted to force the spring 17 longitudinally of the casing and causing one end thereof to engage the toothed wheel 12, which may be called the units wheel, as it is provided with a numbered disc having numbers zero to 9 thereon and operates so as to indicate numbers in the unit place as shown in Figure 1 in which the units place is occupied by a number 9. On each complete rotation of the toothed wheel 12, the tooth 26 engages a tooth 27 in the 60 toothed wheel 11 which may be called the

tens wheel, and causes said wheel to rotate one-tenth of its circumference and registering a number in the opening 20 of the casing, in the tens place.

70 It is obvious that the mechanism as shown is capable of registering numbers to and including 99 and then repeats.

75 While I have described my invention in its preferred form it is obvious that changes may be made therein without departing from the spirit of the invention. I do not therefore wish to be limited to the precise details of construction set forth but desire to avail myself of such variations and modifications as come within the scope of the appended claims.

80 I claim as my invention:

85 1. A device of the class described comprising in combination a casing; a toothed wheel journaled therein; a leaf spring having a U-shaped portion; one side of said U-shaped portion being curved downwardly and the end thereof engaging teeth in said wheel; the other side of said U-shaped portion lying along the upper side of said casing, and means for operating said spring for rotating 90 said toothed wheel.

95 2. A device of the class described comprising in combination a casing; a toothed wheel journaled therein; a leaf spring having a U-shaped portion; one side of said U-shaped portion being curved downwardly and the end thereof engaging teeth in said wheel; the other side of said U-shaped portion lying along the upper side of said casing, a pin 100 engaging a portion of said spring and having a push button thereon.

105 3. A device of the class described comprising in combination a casing; a toothed wheel journaled therein; a leaf spring having a U-shaped portion; one side of said U-shaped portion being curved downwardly and the end thereof engaging teeth in said wheel; the other side of said U-shaped portion lying along the upper side of said casing, said spring having a second U-shaped portion integral with the first, and at right angles thereto; one side of said second U-shaped portion engaging the end of said casing; the other side thereof being curved to fit one side of said wheel for normally retaining said 110 wheel from rotating.

115 4. A device of the class described comprising in combination a casing; a toothed wheel journaled therein; a leaf spring having a U-shaped portion; one side of said U-shaped portion being curved downwardly and the end thereof engaging teeth in said wheel; the other side of said U-shaped portion lying along the upper side of said casing, said spring having a second U-shaped portion integral with the first, and at right angles 120 thereto; one side of said second U-shaped portion engaging the end of said casing; the other side thereof being curved to fit one side of said wheel for normally retaining said 125 130

wheel from rotating, the curved ends of said U-shaped portions normally engaging the other end and the lower side respectively of said casing; a pin passing through and having engagement with a portion of said spring and a push button on said pin for operating the same.

5 In testimony whereof I have signed my name to this specification.
